UNITED STATES PATENT OFFICE

143,457

DESIGN FOR AN INFANT'S SHOE

Arthur P. Williams, St. Louis, Mo., assignor to
Alma Gereau Williams, St. Louis, Mo., doing
business as Alma Gereau

Application July 25, 1945, Serial No. 120,961

Term of patent 7 years

(Cl. D7—7)

To all whom it may concern:

Be it known that I, Arthur P. Williams, a citizen of the United States, residing in the city of St. Louis and State of Missouri, have invented a new, original, and ornamental Design for an Infant's Shoe, of which the following is a specification, reference being had to the accompanying drawing, forming a part thereof.

In the drawing:

Fig. 1 is a top or plan view of an infant's shoe, showing my new design;

Fig. 2 is a side elevation of the shoe embodying my design, and

Fig. 3 is a side perspective view of the infant's shoe shown in the other figures.

The essential features of my design for a shoe of the type as shown reside in the inverted U-shaped design created by the manner in which the lacing is placed on both sides of the shoe upper, in combination with the scalloped top margin of the shoe, all as illustrated.

I claim:

The ornamental design for an infant's shoe, substantially as shown and described.

ARTHUR P. WILLIAMS.
